UNITED STATES PATENT OFFICE.

MARGARET MASSON, OF ATTLEBORO, MASSACHUSETTS, ASSIGNOR TO THE WATSON COMPANY, OF ATTLEBORO, MASSACHUSETTS.

DESIGN FOR A HANDLE FOR SPOONS, FORKS, OR SIMILAR ARTICLES.

47,432.

Specification for Design.

Patented June 8, 1915.

Application filed February 23, 1915. Serial No. 10,152. Term of patent 3½ years.

To all whom it may concern:

Be it known that I, MARGARET MASSON, a citizen of the United States, residing in the city of Attleboro, county of Bristol, and State of Massachusetts, have invented a new, original, and ornamental Design for a Handle for Spoons, Forks, or Similar Articles, which is illustrated in the accompanying drawing, forming part of this application.

design in front elevation. Fig. 2 is a fragmentary perspective view on the line 2—2 in Fig. 1. Fig. 3 is a view of the design in rear elevation.

What I claim is:

The ornamental design for a handle for spoons, forks or similar articles, as shown.

MARGARET MASSON.
